UNITED STATES PATENT OFFICE.

BERNHARD L. SCHMIDT, OF DAVENPORT, IOWA, ASSIGNOR TO WHITE LILY MANUFACTURING COMPANY, OF DAVENPORT, IOWA, A CORPORATION OF IOWA.

GEARING FOR WASHING-MACHINES.

No. 902,174.

Specification of Letters Patent.

Patented Oct. 27, 1908.

Application filed May 21, 1908. Serial No. 434,084.

To all whom it may concern:

Be it known that I, BERNHARD L. SCHMIDT, a citizen of the United States, and a resident of Davenport, in the county of Scott and State of Iowa, have invented certain new and useful Improvements in Gearing for Washing-Machines, of which the following is a full, clear, and exact description.

My invention relates to mechanism for operating washing machines having a rotary reciprocal agitator, and its object is to utilize momentum gearing in connection with this mechanism, which, after it is once in motion, regulates the extent of the movement of the parts of said mechanism and assists the operation thereof. This I accomplish by the means hereinafter fully described, and as particularly pointed out in the claims.

20 In the drawings:—Figure 1 is a side elevation of my improved mechanism applied to a washing machine. Fig. 2 is a view looking at the side of the machine, from a viewpoint at right angles to that shown in Fig. 25 1. Fig. 3 is a view similar to Fig. 2 showing a slightly modified construction of my invention. Fig. 4 is a view similar to Fig. 1 showing yet another modification of the same. Fig. 5 is a view similar to Fig. 2 30 of the modification shown in Fig. 4.

In the drawings, A represents a suitable tub supported on legs, and provided with a cover, a segment of which is securely fastened to the edges of the tub, and the remainder of which forms a lid, hinged to said segment that covers the greater part of the top of the tub. At the center of this lid, there is an agitator shaft *a* whose upper end is journaled in suitable bearing in the screw-plate of a supporting-frame *b*, and whose lower end extends into the tub and is provided with an agitator *c* of a well known design. The upper end of shaft *a* extends through its bearings and is provided with a bevel-gear *B*, which engages a corresponding gear *C* secured to the adjacent end of a horizontal shaft *D*, which latter extends transversely to a point beyond the edge of the cover of the tub, and has bearings in standards arising from the screw-plate of supporting-frame *b*, substantially as shown. At its outer end shaft *D* is provided with a

pinion *c*, which, when the lid of the tub is closed, engages a segmental rack *d* carried by a lever *F*, that is fulcrumed on a suitable pivotal stud *f* projecting from a vertically disposed plate *E* secured to the side of the tub by screws or otherwise, substantially as shown. The boss of rack *d* is provided with an upwardly projecting socket *e* into which the lower end of said lever *F* is inserted and secured. This lever continues upwards in a plane midway between the ends of rack *d* and passes through a suitable eye *e'* made integral with the segment from which the teeth of the rack project. By working this lever back and forth an alternating rotary motion is imparted to shaft *D*, and, through the latter, to the agitator shaft. This arrangement of the rack and pinion *c* permits the lid of the machine to be raised or lowered by the operator at liberty.

In order to derive the advantages which the momentum of the fly-wheel would impart, both during the operation of the machine and at the point of reversal of the movement of the reciprocal elements including the agitator shaft, I have provided the segmental rack with an arm *g* that projects at right angles to the length of lever *F*, preferably, in a plane intersecting the axis of the pivotal stud *f*, the outer end of which has the upper end of a pitman *G* pivotally connected thereto. The lower end of this pitman is pivotally connected to the crank-pin of a comparatively large gear *H* which latter is journaled on a stud *h* projecting from about the height of supporting-plate *E*. The diameter of the perimeter described by said crank-pin is such that, when the lever *F* is moved back and forth to the limit of its movement, said pitman will impart a continuous rotation to gear *H*. Gear *H* meshes with a pinion *I* which is made integral with the inner end of the boss of a fly-wheel *J*, that is journaled upon a pivotal stud *j* projecting from the lower end of a supporting-plate *E*. The fly-wheel *J* revolves in a vertical plane alongside the lower portion of the tub, and is speeded up so as to revolve two or three times as fast as the gear *H*, and when this fly-wheel is once started, its momentum assists in carrying the segmental rack past the point where it re-

verses its movement, as well as that of the pinion *c*, shaft *D*, beveled pinion *C* and *B*, and the agitator shaft, and greatly reduces the manual exertion which would otherwise be necessary to operate the machine.

In Fig. 3 I show a slight modification of my invention, which consists of elongating plate 2 downwards to a point below the plane of the bottom of the tub, and providing it with a bearing 3, and then providing it with legs 4, which extend to and have their lower ends 5 flattened and secured to the inner surface near the feet of the adjacent legs of the tub. Pinion 6 and fly-wheel 7 are journaled in bearing 3, and the gear 8, engaging said pinion is journaled on a stud projecting from plate 2 at a point nearer the bottom of the tub, than as shown in Figs. 1 and 2 of the drawings. The pitman 9 is necessarily made longer in this modification than as shown in said Figs. 1 and 2, but the remainder of the actuating mechanism is the same.

In Figs. 4 and 5 I show yet another modification in which plate 2 remains the same as shown in Fig. 3, but, instead of having the pinion and fly-wheel journaled in its bearing 3, one end of horizontal shaft 10 is journaled therein, which has its end extended through said bearing and provided with a crank 11. This crank is shorter than arm *g*, and is connected thereto by a pitman 12. If desired, a connecting-rod 13 can be pivoted to the crank-pins of crank 11 and connect the same to one end of a treadle 14 whose opposite end may be fulcrumed in a suitable manner to a stud 15 projecting from the lower end of the adjacent leg of the tub. Shaft 10 extends horizontally under the tub to and beyond the opposite side thereof, and has the end opposite the crank journaled in and extending through a bearing 16, in the lower end of a hanger 17. A gear 18 is securely mounted on the said extended end, which engages a pinion 19 on the inner end of the boss of a fly-wheel 20, which latter, together with said pinion is journaled on a stud projecting from the screw-plate 21 of the hanger, which, as shown is secured to the side of the tub.

The advantages of the modification shown in Figs. 4 and 5 of the drawings, is that the weight of the momentum and actuating devices is equally supported by the legs and not borne all on one side of the machine, and, in addition to this, both hand and foot may be utilized to operate the same.

What I claim as new is:—

1. The combination with a rotary reciprocal vertical shaft, a rotary reciprocal horizontal shaft at right angles thereto, means for operatively connecting said shafts, of a lever fulcrumed at its lower end independent of said horizontal shaft, a balance wheel

whose axis is below said lever and parallel to said horizontal shaft and revoluble means actuated by said lever for operating said wheel.

2. The combination with a rotary reciprocal vertical shaft, a rotary reciprocal horizontal shaft at right angles thereto, means for operatively connecting said shafts, of a lever fulcrumed at its lower end independent of said horizontal shaft, an arm projecting from the lower end of said lever, a balance wheel whose axis is below and parallel to said horizontal shaft, and means including a pitman for imparting motion from said arm to said wheel.

3. The combination with a rotary reciprocal vertical shaft, a rotary reciprocal horizontal shaft arranged at right angles thereto, means for operatively connecting said shafts, of a lever fulcrumed at its lower end independent of said horizontal shaft, an arm projecting from the lower end of said lever, a balance wheel whose axis is below and parallel to said horizontal shaft, a pitman whose upper end is pivotally connected to said arm, and a continuously revoluble gear engaged by said pitman that actuates said balance wheel.

4. The combination with a rotary reciprocal vertical shaft, a rotary reciprocal horizontal shaft at right angles thereto, means mounted on the adjacent ends of said shafts for operatively connecting the same and a pinion on the opposite end of said horizontal shaft, of a lever fulcrumed at its lower end independent of said horizontal shaft, a balance wheel whose axis is below said lever and parallel to said horizontal shaft, a segmental rack carried by said lever and engaging the undermost segment of said pinion, and a gear indirectly actuated by said lever for operating said wheel.

5. The combination with a rotary reciprocal vertical shaft, a rotary reciprocal horizontal shaft at right angles thereto, means for operatively connecting said shafts, and a pinion on the outer end of said horizontal shaft, of a lever fulcrumed at its lower end whose axis is parallel to said last mentioned shaft, a segmental rack carried thereby and engaging the undermost segment of said pinion, an arm projecting from the lower end of the same, a balance wheel and means including a pitman for imparting motion from said arm to said wheel.

6. The combination with a rotary reciprocal vertical shaft, a rotary reciprocal horizontal shaft arranged at right angles thereto, means for operatively connecting said shafts, and a pinion on the outer end of said horizontal shaft, of a lever fulcrumed at its lower end, a segmental rack carried thereby and engaging the undermost segment of said pinion, an arm projecting from the lower end of

the same, a balance wheel whose axis is parallel to said last mentioned shaft, a pitman whose upper end is pivotally connected to said arm, and a continuously revoluble gear 5 engaged by said pitman that actuates said balance wheel.

In testimony whereof I have hereunto set

my hand and seal this 29th day of February, A. D., 1908.

BERNHARD L. SCHMIDT. [L. S.]
